United States Patent Office

Des. 186,476
Patented Oct. 27, 1959

186,476

VISUAL RECORDER

Conkling Chedister, Livingston, N.J., assignor to American Design & Development Co., Union, N.J., a partnership

Application March 12, 1959, Serial No. 54,958

Term of patent 14 years

(Cl. D64—11)

Fig. 1

Fig. 2

Fig. 3

Fig. 4

Figure 1 is a front perspective view of a visual recorder, showing my new design;

Figure 2 is a top plan view thereof;

Figure 3 is a side elevational view looking from the right of Figure 2, the side opposite thereto being substantially identical in appearance; and

Figure 4 is a front elevational view thereof, the back being substantially identical in appearance except for the omission of the rectangular window panel.

I claim:

The ornamental design for a visual recorder, as shown and described.
